OUTLET RECEPTACLE

William H. Fabrey and John Weber, Schenectady,
N. Y., assignors to Alpine Electric Corporation,
Schenectady, N. Y., a corporation of New York

Application July 2, 1931, Serial No. 548,451

3 Claims. (Cl. 173—330)

The present invention relates to electrical outlet receptacles, and has for its principal purpose to provide a receptacle body member and contact member having interengaging means for holding 5 the two members in assembled relation.

Heretofore, it has been a customary practice to mount the contact members freely in recesses provided in the body members, the operative relationship of the two members being maintained by a mounting yoke for the receptacle. 10 Prior to the actual mounting of the receptacle, consequently, the members were apt to become disassembled.

Another practice has been to secure the body 15 and contact members together by means of screws or screw-attached clips.

According to the present invention, the body and contact members are provided with mutually 20 engageable means readily brought into operative relation upon assembly and effective to securely maintain the relation of the parts, the improved arrangement being no more expensive to produce than the less satisfactory devices of the prior art.

The invention also relates to simplified screw 25 anchors utilized in uniting the receptacle body members and wall plates.

As illustrative of the invention, we have shown it in the accompanying drawing as applied to a 30 duplex receptacle. It is to be understood, however, that the invention is not limited in its application to this specific type of receptacle.

In the drawing:

Figure 1 is a face view of a receptacle embodying the present invention,

Figure 2 is a side elevation of the receptacle,

Figure 3 is a rear view of the receptacle,

Figure 4 is a rear view of the receptacle partially assembled,

Figure 5 is a section on line 5—5 of Figure 1,

Figure 6 is a section on line 6—6 of Figure 1,

Figure 7 is an elevation of a contact member or conductor bar constructed in accordance with the present invention, and

Figure 8 is an elevation of a screw anchor forming part of the invention.

Referring to the drawing, reference numeral 10 indicates generally a body member of insulating material whose end portions 10a, 10b are provided with service openings 11, 12, 13, and 14 for the reception of the usual type of plug, the intermediate body portion being inwardly offset as at 15. The end portions of the body member have rearwardly extending boss portions 16 and 17, Figs. 2, 4, and 6, provided with recesses 18,

19, 20, and 21 communicating respectively with the service openings 11 to 14. Between the boss portions 16 and 17, the body portion has a further rearwardly extending boss 22 spaced somewhat from the first mentioned boss portions. 5 The boss portion 22 has parallel side walls 23 and 24 terminating upwardly in inwardly extending recesses 23' and 24', these recesses being formed in the sides of the intermediate body member portion 15. 10

Recesses 18 and 20 are aligned longitudinally of the body member, and the walls of the boss portions are provided with aligned kerfs intersecting the recesses so that the walls of recess 18 present a groove 25 and an opposite slot 26 in alignment with a groove 27 and a slot 28 in the walls of recess 20, the bottoms of the slots and grooves forming ledges lying in the same plane. The walls of recesses 19 and 21 are similarly slotted and grooved. 15

Boss portion 22 is provided with a central slot 29 extending longitudinally of the body member, the slot having a central substantially cylindrical enlargement 30. Boss portions 16 and 17 have end recesses 31 and 32. 20

Two conductor bars of identical form are provided, one being particularly shown in Figures 4 and 7. The bar is composed of a strip of spring metal 33 having integral angularly projecting contact fingers 34 and 35 adjacent its ends and 30 lying substantially in the plane of the adjacent strip portions. Intermediate the contact fingers, the mounting strip is offset as at 36 and provided with an ear or protuberance 37 projecting in the same direction as the contact fingers and 35 having an extremity 37', Figure 5, bent in the opposite direction to the offset. The offset portion is provided with tapped apertures at the sides of ear 37 which receive terminal screws 38 and 39. 40

In assembling, the contact fingers are inserted in the recesses 19 and 21, Figure 4, with the ends of the conductor bar engaged in the grooves of the recess walls and the portions of the bar between the contact fingers and the bar offset 45 engaged in the slots of the recess walls. The offset portion of the conductor bar projects externally of the bosses in the lateral recess existing between the latter and the bent portion 37' of the ear 37, the bar yielding outwardly, is slid 50 along the side wall 23 of boss portion 22 until it springs over the seat 23'. As the extremity of the preformed bent portion 37' rides along wall 23, the freely projecting ear flexes so that undue distortion of the contact strip proper is prevented. 55

When the two members have thus been inter-engaged, the end portions of the conductor bar have come to lie against the ledges forming the bottoms of the grooves and slots in the recess walls, this engagement preventing further movement of the conductor bar inwardly of the recesses and the ear preventing outward movement so that the two parts are rigidly united. The edges of the ear 37 and of its bent over portion 37' lie closely between abutment surfaces presented by the body member so that the contact strip is held against longitudinal displacement relative to the latter. The screws 38 and 39 lie in the spaces between the central and outer bosses. It will be understood that the parts can be disassembled by prying the ear 37' out of recess 23' and reversing the assembly operation.

It will be understood that the second conductor bar is assembled in exactly the same manner as the first, its ends being engaged in grooves 25 and 27 directly at one side of the contact fingers and in slots 26 and 28 directly at the other side of the contact fingers. It will be evident that the conductor bars being thus gripped, their portions within the recesses are held against lateral movement, although their free intermediate portions may be sufficiently flexed to engage the ears with the seats. Due to the provision of each recess with the slot and groove for thus gripping the conductor bar, it will be evident that if desired the conductor bar may be made with only one contact finger for use in a simple receptacle. In other words, the conductor bar as shown in Figure 7 might be centrally and transversely cut, as in the sectional view of Figure 5, since, upon being mounted as above described, its tail portion would be permitted to flex under the restraint of the portion adjacent the contact fingers which would be held against lateral movement.

In the illustrated embodiment of the invention, it will be noted that the jack blades are engageable between the contact fingers and the side walls of the boss recess. Consequently, the mounting strip or bus bar portions at the fingers tend to be deflected inwardly upon the insertion of the blades, this deflection being opposed by the edges of the slots and grooves on the opposite sides of the mounting strips from the blades. Furthermore, since the contact fingers, as may be clearly seen from Figure 6, are spaced from the walls toward which they flex when engaged by the jack blades, they may flex freely past the planes of the end portions of the contact strips.

A metal yoke 40 has legs 41 and 42 receivable in recesses 31 and 32 and carries an insulating plate 43 of a shape to cover the rear portion of the receptacle. The yoke and insulating plate have registering slots in register with the slot 29 of boss 22, a screw anchor 44 being passed through the registering slots.

The screw anchor 44 is composed of a bifurcated flat metal strip having a T-head 45 at its closed end, the inner edges of the bifurcations 46 and 47 each being provided with a series of serrations 46' and 47', the serrations of the one series being in staggered relation to the serrations of the other series so as to be adapted to engage the threads of a screw on diametrically opposite sides thereof. The bifurcations are somewhat convergent toward their free ends so as to be expanded upon the engagement of a screw therewith. The anchor has a thickness less than the diameter of the co-operating screw and is readily formed in its entirety in a single stamping operation.

The anchor being inserted in the registering

slots of yoke 40, insulating plate 43 and boss portion 22, with its head abutting the yoke, is adapted to be engaged and spread by a screw 48, Figure 5, passed through the face plate 49.

While we have shown and described a specific embodiment of the invention, it will be understood that many modifications are possible without departure from the scope of the invention, and, accordingly, we do not limit ourselves except as in the following claims.

We claim:

1. A duplex receptacle comprising a one-piece body member provided with pairs of service openings in its front face and with rearwardly opening recesses behind said service openings and communicating with the latter, said body member having rearwardly open lateral recesses in its central portion, there being rearwardly open slots connecting the ends of said lateral recesses with said rearwardly opening recesses, a pair of contact strips each having angularly projecting contact fingers at its end portions, said strips being arranged on edge with their medial portions in said lateral recesses and their end portions in said rearwardly opening recesses with said contact fingers operatively disposed in the latter relative to said service openings, said strips being closely engaged in said slots between the end and medial portions of the strips, said lateral recesses having wall portions extending longitudinally of the body members forwardly of said contact strips and terminating forwardly in inwardly directed ledges, said contact strips having freely forwardly projecting integral medial portions with inturned ends engaged over said ledges to hold said strips against rearward displacement; said freely projecting portions being adapted to flex when upon assembly of the contact strips with the body member from the rear of the latter, said inturned ends being pre-formed, the extremities of said ends ride over said longitudinally extending wall portions, such flexing preventing undue distortion of said contact strips.

2. A duplex receptacle comprising a one-piece body member provided with pairs of service openings in its front face and with rearwardly opening recesses behind said service openings and communicating with the latter, said body member having rearwardly open lateral recesses in its central portion communicating at their ends with said rearwardly opening recesses, a pair of contact strips each having angularly projecting contact fingers at its end portions, said strips being arranged on edge with their medial portions in said lateral recesses and their end portions in said rearwardly opening recesses with said contact fingers operatively disposed in the latter relative to said service openings, said lateral recesses having wall portions extending longitudinally of the body members forwardly of said contact strips and terminating forwardly in inwardly directed ledges, said contact strips having freely forwardly projecting integral medial portions with inturned ends engaged over said ledges to hold said strips against rearward displacement, the body member also having abutment portions cooperating with the edges of said inturned ends to hold said contact strips against longitudinal displacement relative to said body member.

3. A duplex receptacle comprising a one-piece body member provided with pairs of service openings in its front face and rearwardly opening recesses behind said service openings, said body

member having rearwardly open lateral recesses in its central portion and having rearwardly open slots connecting the ends of said lateral recesses with said rearwardly opening recesses, 5 said slots being spaced from the side walls of said rearwardly opening recesses, the end walls of said last-named recesses having grooves opposite said slots and spaced from the side walls of said last-named recesses, conductor strips 10 disposed on edge with their medial portions in said lateral recesses and with their end portions disposed in said slots and in said rearwardly opening recesses, the extremities of said strips being disposed in said grooves, and contact fingers on 15 the end portions of said strips in said rearwardly

opening recesses, the blades of a cooperating jack inserted in a pair of said service openings being engageable with pairs of said fingers, lateral deflection of the conductor strip portions at the engaged fingers being opposed by the edges of the grooves and slots on the opposite side of the conductor strips from the engaged blades, clearances existing between the contact fingers and the side walls of said rearwardly opening recesses to enable the fingers to be forced freely beyond 10 the planes of the conductor strips when engaged by the blades. 5
